INKING ROLLER

Theodore J. Kauffeld, New York, N. Y.

Application May 31, 1941, Serial No. 396,009

10 Claims. (Cl. 91—67.8)

This invention relates to inking rollers of the type employed for distributing ink on printing machinery. More particularly, the invention is directed to the resilient inking rollers which are used in a distributing system which feeds ink from a supply, breaks it up into a film of uniform thickness and consistency, and transfers this ink to a printing surface.

Resilient inking rollers presently used comprise a central rigid shaft or core around which is cast or moulded a layer of resilient material such as a compound of glue and glycerine, rubber, or other suitable material. This layer is cast, moulded, or machined to a specific outside diameter in order that the roller may rotatably contact other rollers in a train, or contact a moving printing surface.

There is a tendency with some types of compound covered rollers, particularly those in which the compound consists of a mixture of glue and glycerine, for the cast or moulded compound to reach its melting point during extremes of temperature or service. This melting and failure occurs first at the core of the roller where the metal core and resilient composition join, and, after primary failure at the core, the roller will usually break down completely due to the stresses of contact under which it operates.

It is an object of this invention to provide a roller which will not melt down during the most severe conditions of operation. A further object is to provide a roller, the core of which may be kept at a temperature well below the temperature of the room and which is designed for efficient transfer of heat.

It is also an object of the invention to provide a roller core of improved design which has a more efficient resistance to bending stresses for a given quantity of material.

With these and other objects in view, which will be apparent throughout the description, the invention resides in the novel construction, combination, and arrangement of parts substantially as hereinafter described, and more particularly defined in the appended claims, it being understood that such changes in the precise embodiment of the invention may be made as come within the scope of the claims.

The accompanying drawing illustrates examples of the physical embodiment of the invention constructed according to the best modes so far devised for the practical application of the principles thereof, and in which:

Figure 1 is a perspective view of a roller ac-

cording to the invention with a cut-away portion showing the core construction.

Figure 2 is a fragmentary longitudinal section thru the roller and its core.

Figure 3 is a transverse section thru the roller and core at 3—3 Figure 2, and

Figures 4 and 5 are side views partially cut away showing alternative core arrangements.

The general type of roller system with which my roller is used comprising ink fountain, ductor roller, ink drums, vibrator rollers, and distributor rollers is well known in the art and requires no special description herein.

The resilient roller, Figure 1, includes a core, generally indicated at 10, covered with a resilient composition 12. The core is mainly of hollow steel tubular construction as shown in Figures 2 and 3, fitted in its ends with gudgeons 11 used to support the roller for rotation about its longitudinal center. Bearing surfaces 17, concentric with the roller core, are included on the outside end of the gudgeons, the opposite end 18 of gudgeons 11 being fitted to the interior end of the tube 16 by pressure fitting, welding, or the like so that the core and gudgeon are, for practical purposes, integral.

Each gudgeon is bored throughout its entire length to provide for the passage of a gas or fluid cooling medium used to carry heat away from the hollow core. The bearing ends 17 of the gudgeons may be threaded on the inside as shown in Figure 3 for the purpose of adapting a suitable coupling to supply and carry away a cooling medium during rotation of the roller.

The exterior surface of the tubular core center is provided with radially projecting metal fins 15, spaced about the circumference of the tube 16 and extending for the full length of the core center. These fins are of relatively thin section and securely imbedded in the tubular core center. They are sufficient in quantity and dimension so that the conduction of heat between the metal core and the resilient composition coating of relatively high heat flow resistance approaches or equals the conduction of heat between a cooling medium of relatively low resistance to the flow of heat and the inner metallic surface of core 10.

The exterior surface proportions of the core may differ for various materials used, both in the construction of the core and also in the resilient surface. Other factors which will determine, to some extent, the required exterior surface area of the core are the operating conditions, which affect the quantity of heat conducted to the core.

Alternative fin construction may be employed

to substitute for the longitudinally disposed fins as shown in Figure 1. Figures 4 and 5 show alternatives, where in Figure 4 the fins 15' are applied to the core center in spiral fashion, and in Figure 5 fins 15'' are applied transversely of the core center in disc form. However, it is preferred to use the longitudinal or spiral fin construction as shown in Figure 1 or Figure 4 respectively inasmuch as there is added resistance to bending stresses gained by adopting one of these types. As a consequence of using one of these types of construction with an improved section modulus compared to the conventional cylindrical roller core, it is possible to reduce the material used and effect a saving in this manner.

The core may be kept cool by contact circulation of air or any other satisfactory gas or liquid medium within the tubular core center. It may be desirable to have the cooling medium enter the tube at one end, pass thru the inner opening and discharge from the other end or; it may be found more desirable to have the intake and discharge on the same end. In the case of the latter, one of the gudgeons would necessarily be blocked off on its end to the passage of the cooling medium.

In application, the primary essentials are to facilitate the transfer and limit the storage of heat at the surfaces where the composition contacts the roller core, and to provide relatively larger contact surface to materially decrease the concentration of heat to be dissipated.

It is to be understood that the form of my invention herewith shown and described is to be taken as a preferred example of the same, and that various changes in the shape, size, and arrangement of parts may be resorted to without departing from the spirit of my invention, or the scope of the subjoined claims.

Having thus described the invention, what is claimed as new and desired to be secured by Letters Patent is:

1. In a resilient roller for inking, in combination, a metallic core, a plurality of metal heat transfer surfaces integral with and projecting from the outside surface of the core, and a resilient composition contacting said heat transfer surfaces and forming a cylindrical inking surface.
2. In a resilient roller for inking, in combination, a hollow cylindrical core, a plurality of

5 metal heat transfer surfaces integral with and projecting from the outside surface of the core, and a resilient composition contacting said heat transfer surfaces and forming a cylindrical inking surface.

3. In a resilient roller for inking, in combination, a hollow cylindrical core, two concentric supports integral with the ends of the core, heat transfer surfaces integral with and projecting 10 from the core, and a resilient composition contacting said heat transfer surfaces and forming a cylindrical inking surface.

4. An inking roller core comprising a tubular central portion, a plurality of heat transfer fins 15 projecting from the outside surface of the tubular central portion, and gudgeons integral with the ends of the core to support it for rotation about a central longitudinal axis.

5. An inking roller core comprising a tubular central portion, a plurality of heat transfer fins projecting from the outside surface of the tubular central portion, and gudgeons integral with the ends of the core to support it for rotation about a central longitudinal axis, at least one of 20 said gudgeons including a communicating passage from the interior of the tubular central portion to the outside of the gudgeon.

6. An inking roller core comprising a cylindrical central portion and heat transfer fins secured to and projecting outwardly from said central portion.

7. An inking roller core comprising a cylindrical central portion and heat transfer fins secured to and projecting radially outwardly from said central portion.

8. An inking roller core comprising a cylindrical central portion and spirally disposed heat transfer fins secured to and projecting outwardly from said cylindrical central portion.

9. An inking roller core comprising a cylindrical central portion and heat transfer fins secured to and projecting transversely from the cylindrical central portion.

10. An inking roller core comprising a cylindrical central portion, longitudinally disposed web sections radiating from said cylindrical central portion, and concentric supports integral with and projecting from the ends of the cylindrical central portion.

THEO. J. KAUFFELD.
